UNITED STATES PATENT OFFICE.

THOMAS E. PRAY, OF CHICAGO, ILLINOIS, ASSIGNOR TO GOODMAN MANUFACTURING COMPANY, OF CHICAGO, ILLINOIS, A CORPORATION OF ILLINOIS.

APPARATUS FOR HANDLING LOOSE MATERIALS.

Application filed August 12, 1926. Serial No. 128,736.

This invention relates to a new and useful apparatus for handling loose materials, and has among other objects to provide a new and improved apparatus of this description 5 for moving loose material from one place to another by means of a scraper, and for guiding, controlling and actuating the scraper during such operation. The device while capable of use in many situations and for 10 many purposes wherein it is desired to transfer loose material from one point to another is practically adapted for use in coal mining operations.

More specifically, my invention relates to 15 improvements in devices of the character disclosed in an application, Serial Number 352,413, filed January 19, 1920, by Charles E. Davis, wherein the loading apparatus is provided with a new and improved arrangement of parts, affording greater rope 20 capacity and operable in thinner seams of coal, and with the provision whereby material may be loaded from one side of the device as well as from the other by simply 25 interchanging the functions of the control and tail lines. This feature of my invention improves upon other apparatus of this class in that material can be gathered equally as well from one side of the device as from 30 the other without causing undue wear on the draft ropes by various rearrangements of ropes about guide sheaves such as have heretofore been necessary when changing the device to gather material from opposite 35 sides.

The invention may be best understood by reference to the accompanying drawings wherein:

Figure 1 is a side elevation of the device 40 embodying my invention;

Figure 2 is a fragmentary plan view of the device shown in Figure 1;

Figure 3 is a vertical section taken on line 3—3 of Figure 2;

Figure 4 is a sectional view taken on line 4—4 of Figure 2;

Figure 5 is a view showing a mine room with one form of my device embodying my invention wherein the material is being

gathered from one side of the apparatus; 50 and

Figure 6 is a view showing a mine room wherein the material is being gathered from the opposite side of the device.

Referring now to the details of the drawings shown in Figure 5, I have illustrated a scraper 1 adapted for reciprocable movement by means of a head line 2 and a tail line 3. In the typical loading arrangement shown, the tail line passes over a sheave 4 at the far end of the working face along which the loose material is to be gathered, and the head line passes over a sheave 5. This latter sheave is connected with a control line 6, which passes about a fixed sheave 7. The sheave 5 is movable but may be fixed in position when desired. It will be noted, with reference to Figure 6, that the positions of the control, head and tail lines have been reversed so as to pull the scraper in the 70 opposite direction, from that shown in Figure 5. This feature of my invention will be more fully described in another portion of this specification.

In the construction illustrated, I provide 75 a portable controlling mechanism for these lines. This mechanism consists of a truck 8 having a pair of longitudinally spaced axles 9, 9 with supporting wheels 10, 10 thereon. The truck is provided with a series 80 of winding drums, including a head line drum 16, on a vertical shaft 17 to the rear of the rearmost driving wheel and adjacent the inner side of the left rear driving wheel, a drum 18 also on shaft 17 and disposed 85 below the drum 16, and a drum 19 on a vertical shaft 20 forward of the shaft 17 but rearward of the right rear driving wheel 10 and adjacent the inner side of said driving wheel. The location of the shaft 20 forwardly of the shaft 17, and the mounting 90 of two drums on one shaft, one beneath the top of the rearmost supporting wheel 10 and the other above said wheel, and the placing of a third drum on the second shaft, 95 permits the use of drums of a larger diameter than could be utilized if the two shafts were placed side by side in line with each other

or if the three drums were mounted side by side on separate vertical shafts. It also permits the machine to be built to a much lower height than would be possible if all 5 three rope drums, of similar capacity as those herein, were mounted on a common horizontal shaft.

The peripheries of drums 18 and 19 project well beyond the lateral boundaries of the 10 portable controlling mechanism and are all identical in construction. Each drum has a suitable brake 21 and each drum has substantially the same rope capacity. Thus it may be seen that the rope wound on the drum 18 15 may be used to perform the same functions as the rope wound on the drum 19.

All three drums are driven by a suitable motor which is herein illustrated as an electric motor 22. Said motor is connected by 20 a pinion 23 to a gear 24 to rotate a shaft 25. Rotation of the shaft 25 rotates a bevel pinion 26 meshing with a bevel gear 27 which in turn rotates a shaft 28 carrying a spur gear 29 and having connection with gears 30 and 31. Rotation of the gears 30 and 31 rotates the shafts 17 and 20 and transmits power to 25 the rope drums when connected thereto by suitable means which make it possible to selectively drive these rope drums. Said 30 means as herein illustrated comprises suitable clutches which are shown as friction clutches of similar construction. Each of said clutches comprises an expanding friction band 33 which when expanded against 35 an inner periphery 32 of the rope drum transmits power from the drive shaft to the drums, but allows the drums to ride freely on the shaft when contracted.

As may be seen from the drawings one end 40 of the friction band 33 is connected at 34 with a member 35 which is keyed to the drum drive shaft and rotates therewith. The other end of the band 33 is connected to one end of a bell crank lever 36 which is 45 pivoted to the member 35. The other end of the bell crank lever 36 is connected by a link 37 with a sliding collar 38. Said collar has a groove 39 containing a fork 40 which slides the collar up or down on the 50 drive shaft by means of suitable lever devices. It will thus be observed that when the sleeve is moved down in the case of the drums 16 and 19, and up in the case of the drum 18, the link 37 pulls down on the end 55 of the bell crank lever 36 and rocks the bell crank lever to bring the ends of the friction band closer together and release the clutch. Movement in the other direction straightens out the link 37 and lifts up the 60 end of the bell crank lever 36 which separates the ends of the friction band and applies the clutch. It will here be seen that the shafts 17 and 20 are simultaneously driven from the common member 29. Since 65 the drums 18 and 19 are interchangeable, they

should both wind in at the same time and should wind in as the drum 16 unwinds or should both unwind as the drum 16 winds. The drum shafts 17 and 20 rotate in the same direction so it is only necessary that the 70 rope on the drum 18 be wound in an opposite direction to the rope on the drum 16 to accomplish this result. The motor 22 is preferably of the reversible type and reversal thereof causes the shafts 17 and 20 to rotate 75 in opposite directions, and reverses the direction of rotation of the rope drums.

Means are also provided for holding the drums 18 and 19 against rotation when desired. In the construction shown, I have 80 provided a brake band on each of these drums for this purpose. A flanged portion 41 integral with each drum is provided having thereon a brake band 42. A projection on one end of this band is connected to a 85 fixed point 43. The other end is connected to a lug 44 which is connected to a rod 46 having a head threaded to one end and an eyepiece to the other end. One arm of a bell crank lever 59 is pivoted to the other end of 90 said bell crank lever. Pressure on the lever 60 applies the brake, and vice versa.

The truck 8 is propelled by the motor 22 through pinion 23, gear 24, and a gear 47 which is free to rotate on a shaft 48. A 95 suitable jaw clutch 49 is provided to connect the gear 47 with the shaft 48 so as to selectively drive said shaft. When the clutch jaws are engaged the shaft 48 will rotate the bevel pinion 50 which in turn will rotate the bevel gear 51, shaft 52 and sprocket 53. A chain 54 connects the sprocket 53 with a sprocket 55 keyed to the forward truck axle. The forward axle drives the rearward axle through sprocket 56, chain 57 and sprocket 105 58. Thus rotation of the sprocket 53 rotates the forward and rear truck axles which drives the wheels and propels the truck.

The truck is provided with an inclined 110 chute or guide for the scraper, 65. This guide is so arranged that when the scraper reaches the truck it is pulled up along this guide carrying the material with it, and the end of the guide is so placed that the material from the scraper is discharged into a receiving device. Referring to Figure 1 it will be seen that the portion of said guide chute immediately above the winding drums extends in a horizontal plane. This substantially decreases the height of my device, both 115 while loading or travelling about the mine and provides a machine of less vertical dimensions than other machines of this type. The ends of the guides 66 and 67 are so arranged that they may be moved out of the way when the truck is being transported. The truck is provided with an extension arm 70 having a direction changing device 71 about which the head line 2 passes. This head line passes from the scraper about this 120 125 130

pulley through guide rollers 72 to the head line drum 16. Since the shafts 17 and 20 rotate in opposite directions, it will be seen that the head line lengthens while the tail line shortens and vice versa, without regard to whether the drums 19 or 18 are used as tail line drums. It will also be noted that the rope from the drum 19 pays directly off the drum beyond the lateral boundaries of the guide chute, while the rope from the drum 18 pays off the inner side of the drum and requires a guide sheave 73 to guide it beyond the boundary of the guide chute. The extension arm 70 is arranged so that it may be moved out of the way when the truck is being transported.

The use and operation of my invention is as follows:

When the device is to be used in a mine, the truck with the incline and control mechanism is run to the mouth of the room as illustrated in Figure 5. A car 75 is run in proximity with the outer end of the incline and the direction changing devices 4 and 7 and guide 76 are placed in position. The coal has been mined from the wall 77 and is lying on the floor near this wall. The pulling forward of the scraper 1 along the mine wall 77 causes it to be loaded with loose coal. When the scraper is loaded it is desirable to turn it so that it can be moved toward the entrance of the room. This turning must be gradual and is done by allowing the direction changing device 5 to move away from the direction changing device 7. This is accomplished by releasing the brake on the control line drum 19, (Figure 5). The scraper is now pulled down by the head line 2 to the incline or guide 65 and is pulled up along said guide to the end thereof when the material is discharged into the car 75. The scraper 1 is open at the bottom and at one end so it may be easily discharged. After the scraper has been unloaded it is moved back to its initial position as shown in Figure 5. During the backward movement of the scraper the tail line 3 is wound in on its drum 18 while the head line drum 16 allows the head line 2 to unwind. The clutch to the control line drum 19 is applied to wind the control line on its drum until the direction changing device 5 is in proximity to the direction changing device 7 when the control line drum clutch is released and the control line drum brake is applied to hold the movable direction changing device 5 until the scraper has again been loaded and it is desired to turn the scraper from the face of the coal to the room entry.

When it is desired to gather material from the right hand side of the device (Figure 6) instead of from the left hand side (Figure 5) it is only necessary to interchange the functions of the control and tail line drums.

To interchange these ropes it is only necessary to disconnect the tail line 3 from the scraper 1 and connect it with the direction changing device 5 while the control line 6 is disconnected from the sheave 5 and connected to the scraper 1 and the guide sheaves and deflector are placed in their respective positions as illustrated.

While I have shown and described one embodiment of my invention, it will be understood that the arrangement and construction of the various parts may be altered without departing from the spirit and scope thereof. Furthermore, I do not wish to be construed as limiting myself to the particular construction illustrated excepting as it may be specifically limited in the appended claims.

I claim as my invention:

1. A device for handling loose material comprising a scraper with suitable draft means for moving the same, a portable power device for said scraper and draft means, axles on said power device having supporting wheels thereon, an inclined chute extending over said power device, and winding devices for said draft means mounted on vertical axes offset from each other beneath said chute and having their peripheries extending beyond the lateral boundaries of said chute.

2. A device for handling loose material comprising a scraper with suitable draft means for moving the same, a portable power device for said scraper and draft means, axles on said power device having supporting wheels thereon, an inclined chute extending over said power device, and winding devices for said draft means mounted on vertical axes rearwardly of the rearwardmost pair of supporting wheels and disposed beneath and having their peripheries extending beyond the lateral boundaries of said chute.

3. A device for handling loose material comprising a scraper with suitable draft means for moving the same, a control line for said scraper, a portable power device for said scraper and draft means, axles on said power device having supporting wheels therefor, an inclined chute extending over said power device, and a plurality of winding drums for said draft and control means, certain of said winding drums being mounted on a common vertical shaft and selectively driven thereby, and another of said drums being mounted on another vertical shaft and having selective driving connection therewith.

4. A device for handling loose material comprising a scraper with suitable draft means for moving the same, a control line for said scraper, a portable power device for said scraper and draft means, axles on said power device having supporting wheels

therefor, an inclined chute extending over said power device, and a plurality of winding drums for said draft and control means, certain of said winding drums being mounted on a common vertical shaft and selectively driven thereby and another of said drums being mounted on another ver-

tical shaft forward of said first mentioned shaft and having selective driving connection therewith.

Signed at Chicago, in the county of Cook and State of Illinois, this 10th day of August, A. D. 1926.

THOMAS E. PRAY.
